A. J. SALISBURY, OF SAN BUENA VENTURA, CALIFORNIA, ASSIGNOR TO
HIMSELF AND THOMAS R. BARD, OF SAME PLACE.

Letters Patent No. 79,400, dated June 30, 1868.

IMPROVED REAMER FOR WELLS.

The Schedule referred to in these Letters Patent and making part of the same.

TO ALL WHOM IT MAY CONCERN:

Be it known that I, A. J. SALISBURY, of San Buena Ventura, in the county of Santa Barbara, and State of California, have invented a new and improved Expanding Reamer for Petroleum and other Artesian Wells; and I do hereby declare that the following is a full, clear, and exact description thereof, which will enable those skilled in the art to make and use the same, reference being had to the accompanying drawings, forming part of this specification, in which—

Figure 1 is a side view of the reamer contracted for descent through the tubing.

Figure 2 is a side view of the same when the same is expanded.

Figure 3 is a detail section of the toggle-joint through the line *x x*, fig. 2.

Similar letters of reference indicate corresponding parts.

This invention relates to a method of expanding branches of a well-reamer by a positive downward thrust of the superincumbent shafting, by which the reamer is actuated in the operation of reaming, and consists of a toggle-joint attached to and between the said branches a certain suitable distance from the points of the latter, and operated by the direct vertical thrust of the shafting, to which the reamer is attached, acting upon a shank pivoted to the toggle-joint, together with other devices perfecting the whole, as will be hereinafter more fully set forth.

In certain sections of the United States, as the Pacific coast, the formation in which petroleum is found is a soft friable shale, generally overlaid by beds or washes of sand, gravel, boulders, &c., and alternating with bands of sandstone or strata of flint, or other silicious formation, as indurated shale, and the like.

These conditions render it necessary, in sinking an artesian well, to employ metallic tubing for the purpose of following down the boring-tool at each successive point of its descent, for the purpose of preventing the so-called caving in of the walls of the well at those points where sand or friable formation is penetrated.

The employment of tubing, as above described, requires that the drill should be worked within the tubing, and therefore the well bored by it will not permit the descent of the tubing until the hole is reamed out by a second tool or reamer. This reamer is required to be expandible, so that it shall enlarge the well, and so permit the tubing to descend.

Such expanding reamers have been used heretofore, but their branches were expanded and so held by spring-tension only, which tension was not sufficient for the purpose when acting against any positive resistance, as rock.

My improvement obviates this disadvantage, and supplies a rigid resistance to the contraction of the branches of the reamer, which enables it to ream out and enlarge the well to a diameter suitable for the ready descent of the tubing, as will now be shown.

A A are the branches of the reamer, which connect with each other, and form a whole by means of a cross-bar, B, as shown.

Through a central hole in this cross-piece works a shank, C, which passes down between the branches A, and is connected with the toggle-bars D at their common joint, e, and by the same pin, a, which completes the joint. These toggle-bars are pivoted to the branches A by stout pivot-pins, b, through the lugs d and the tenon-ends of the toggle-bars, as shown.

Thus a toggle-joint is provided which, by means of the shank, will accomplish the expansion and contraction of the branches, as desired, and when expanded for the purpose of reaming, the said toggle-joint will hold them rigidly, and prevent their yielding when encountering rock or other resistance.

The shank is provided with a screw-head, F, for attaching it to the hollow screw on the stem or shafting, precisely as the drill or other tools are attached. A shoulder, G, prevents the shank from being thrust too forcibly upon the toggle-bars when the latter have expanded the branches to their limit, as shown in fig. 2. A helical spring, S, is coiled around the shank, and exerts its tension against the shoulder H and the cross-bar B,

as shown. The object of this spring is not to preserve the rigidity of the extended branches, for that is effectually accomplished by the toggle-joint and shank, but is simply to assist the expansive tension of the branches themselves, which are of steel.

When the reamer is to be employed in enlarging the hole made by the drill in rock or other hard medium, the branches A are held contracted by a wire passing through holes in the said branches, and brought down under the cutting-edges of the same, and locked or twisted. The position and arrangement of the wire are shown in fig. 1. The reamer is then attached to the stem or shafting by means of the screw F, as aforesaid.

The reamer is thus permitted to pass down through the tubing, and having arrived at the bottom, a blow or two is sufficient to sever the wire and leave the branches free to expand, and the shank pressing upon the joint of the toggle-bars, expands the said branches and holds them rigidly, for the toggle-bars being straightened, supply an unyielding cross-brace, which will not permit the branches to yield when the operation of reaming is going on.

Other equivalent devices may be employed to maintain this desirable rigidity, such as a cam, or wedge, or eccentric-disk, or screw, but the principle will be the same, to wit, the expansion and rigid holding of the branches by means of the downward thrust of the shank C, or its equivalent, and I desire to be understood as having known and contemplated such modifications, but present the arrangement set forth in the above as being the simplest, and one that has stood the test of many months' experience in sinking wells through difficult alternations of sand and rock strata, where the expanding reamers as heretofore made failed utterly to accomplish the satisfactory progression of the work.

When the reamer is to be withdrawn, the sides of the expanded branches encountering the bottom edges of the tubing present a slight resistance, which enables the shank to actuate the toggle-joint upward, and thus draw the branches inward, so as to conform to the diameter of the tubing.

This improved reamer is simple, cheap, efficient, and durable, and supplies a want long felt by those interested in the sinking of petroleum-wells.

I claim as new, and desire to secure by Letters Patent—

The combination of the branches A, cross-bar B, toggle-bars D, shank C, and spring S, substantially as and for the purpose set forth.

The above specification of my invention signed by me, this fourteenth day of October, 1867.

A. J. SALISBURY.
